UNITED STATES PATENT OFFICE.

ROBERT J. VICTOR, OF HUDDSONDALE, PENNSYLVANIA.

MINCING-KNIFE.

SPECIFICATION forming part of Letters Patent No. 293,542, dated February 12, 1884.

Application filed April 16, 1883. (No model.)

To all whom it may concern:

Be it known that I, ROBERT J. VICTOR, of Huddsondale, in the county of Carbon and State of Pennsylvania, have invented certain new and useful Improvements in Mincers, of which the following is a specification.

My invention consists in certain Improvements in mincers or hashers held and operated by hand, whereby they are simplified in construction and made more efficient in operation.

In the accompanying drawings, Figure 1 is a perspective view of my improved mincer with all the parts in place; Fig. 2, a detail view, showing the manner of connecting the blades to the handle; and Figs. 3 and 4 illustrate the form of blade employed and the manner of connecting them together.

To construct my improved mincer I provide a number of triangular metallic knives or blades, A B C D, preferably shaped like a high isosceles triangle, as shown in Figs. 3 and 4. The blades may be conveniently cut from a strip of sheet metal without waste, and their bases are sharpened to form cutting-edges *a*. The apexes of the blades are cut away to form shanks *b*, with shoulders *c*, and are formed with correlative slots, by which they may be connected together and held by the handle, at the same time mutually supporting and strengthening each other. In Fig. 3 is shown the manner of forming and cutting the blades when three knives are employed. The blade A is formed with a single slot, *d*, which extends from the apex down through the center of the blade, terminating a short distance from the base, leaving a bridge, *e*. The blade B is formed with a short slot, *f*, extending from its base upward, and being equal in length to the width of the bridge *e*, and a longer slot, *g*, similar to but somewhat shorter than the slot *d*. A bridge, *h*, separates the slots *f* and *g*. The blade C is formed with a single slot, *i*, which extends from the base upward, and which equals in length the distance from the bottom of the slot *g* to the cutting-edge of the blade B. The width of the slots should be equal to the thickness of the blades. The blades are put together by first passing the blade B down into the slot *d*

of the blade A until the bridge *h* rests upon the bridge *e*, and then passing the blade C down into the two slots *d* and *g* until the bridge *h* enters the slot *i*, and the blade C rests upon the bridge *h*. This will bring the 55 cutting-edges in line and the blades will be disposed radially, as shown in Fig. 1.

I preferably employ a handle, such as shown in Figs. 1 and 2, in which a stock, E, is provided with a ferrule, J, against which the shoulders *c* of the blades bear, and sockets for receiving the shanks *b*. As thus constructed, the mincer is strong, durable, and inexpensive, and does the work efficiently. By having the knives disposed radially, as shown, 65 and decreasing in width from the base to the handle, the minced substance will be less likely to back between the blades.

My improvements are especially designed for mincing meat and vegetables, but may also 70 be employed in meat-tenderers and other kindred instruments.

In Fig. 4 is shown the manner of disposing the slots when four blades are employed. It will be observed that the first blade, A, in the 75 series is formed with a single slot extending from the top downward, and the last blade, D, with a slot extending from the bottom upward, and the intermediate blades are each formed with two slots, with a narrow bridge between 80 them. The upper slot in the first blade extends through nearly the entire length of the blade, and the upper slots in the intermediate blades decrease in length as the series advances. The lower slots (which are formed 85 in all the blades but the first one) equal in length the difference between the entire length of the preceding blade and the length of its upper slot. Following this rule the number of blades may be increased. I prefer, however, 90 to employ three, or, at most, four blades.

I claim as my invention—

1. The combination of the handle and the blades arranged radially therein, the first blade of the series being provided with a single long slot, the last blade with a short slot, and each of the intermediate blades with both a long and a short slot, as set forth, by which the blades may all be connected together, substantially as described.

2. The combination, substantially as described, of the handle and the blades formed with correlative slots, whereby they may be connected together, as set forth, and with 5 shanks and shoulders, by which they may be fixed on the handle.

In testimony whereof I have hereunto sub-

scribed my name this 13th day of April, A. D. 1883.

ROBT. J. VICTOR.
